AUTOMATIC PRESS FEEDING MECHANISM

Application filed September 7, 1929. Serial No. 390,926.

My present improved press feeding mechanism is designed more particularly for feeding sheets of paper onto the platens of so-called Gordon or platen printing presses, one main object of the invention being to provide a sheet feeding mechanism that may be readily attached to existing presses of this type with little or no alteration in their structure, and that when attached or installed will not unnecessarily encumber the press or hamper the operator in attendance thereon. The device or machine is designed to pick up and transfer the sheets by pneumatic suction and the invention has as a further object the controlling of such suction conjointly with the movement of the picker fingers so as to locate the sheets accurately on the platen of the press. Still another object of the invention is to render the mechanism simple and compact and to reduce the number of operating parts so that the requirements in the way of attention and repair may be reduced to a minimum.

To the accomplishment of the foregoing and related ends, the invention, then, consists of the means hereinafter fully described and particularly pointed out in the claims, the annexed drawings and the following description setting forth in detail certain mechanism embodying the invention, such disclosed means constituting, however, but one of the various mechanical forms in which the principle of the invention may be used.

In said annexed drawings:—

Fig. 1 is a side elevation showing my improved sheet feeding mechanism as attached to a press of the type in question, the latter being shown in this, as well as in the succeeding figures, in dotted outline only; Fig. 2 is a plan view of the mechanism with portions of the press only appearing; Fig. 3 is a front elevation of such mechanism and press; Fig. 4 is a transverse vertical section of a portion of the mechanism, the plane of the section being indicated by the line 4—4, Figs. 2 and 3; Fig. 5 is likewise a vertical section of the same portion of the mechanism, the plane of such section being at right angles to that of Fig. 4, substantially as indicated by the lines 5—5 on Figs. 1, 2 and 4; Fig. 5a shows the parts in different operative position; Fig. 6

is a side elevation, on a somewhat larger scale, of the table whereon the stack of blank sheets is supported together with operating means whereby such table is advanced and retracted in unison with the movement of the picker fingers; and Fig. 7 is a side elevation of such table on the same scale as in Fig. 1, but showing same in a different operative position.

The press illustrated in the drawings, as previously indicated, is of the familiar platen or Gordon type and need not be further described than to note the oscillatorily mounted platen 1 on which the sheet requires to be placed preliminarily to being brought into contact with the form by the conjoint movement of such platen and of the opposite bed 2 which carries such form in a suitable chase, not shown. In the several general views appearing in the drawings, the press is shown with the platen in its sheet receiving position, the grippers 3, whereby the sheet is held onto the platen during the printing operation, being suitably raised.

The principal support for the feeding mechanism of present interest is a vertical tubular shaft or column 5 which, as shown, is preferably installed on the left side of the main frame of the press so as to lie laterally adjacent to the platen in its aforesaid sheet receiving position, the upper end of the shaft rising a suitable distance above such platen. The manner in which said shaft is attached to the frame of the press is a matter of indifference, but in the illustrative construction shown (see Fig. 1) I utilize a plate 6 that is adapted to be directly bolted against the corresponding side frame of the press, such plate being provided with a lug or bracket 7 in which the lower end of the shaft is fixedly held, while a second bracket 8 secures the upper portion of the shaft directly to the aforesaid main frame at an adjacent point.

The present feed mechanism is designed to operate in conjunction with a magazine or table 9 for the blank sheets that is located directly in front of the platen and is inclined downwardly in a direction away from such platen at an angle sufficient to cause the stack of paper to rest in a correspondingly

inclined position against the back plate 10 on said table. Such back plate will ordinarily be longitudinally movable along the top of the table to advance the stack as successive sheets are removed from the front thereof, but inasmuch as such advancing means form no part of the present invention, it is not deemed necessary to illustrate the same and for the same reason the means, which will ordinarily be provided for vertically adjusting the elevation of the table, are not illustrated. However, as previously indicated, the table for the purpose in hand requires to be reciprocated longitudinally towards and from the platen 1 or rather the picker fingers which serve to transfer successive sheets from the table to the platen. To this end the table is slidably mounted on a base 11 that is provided with a rack 12 wherewith a spur gear, rotatably mounted on the under side of the table, meshes. As a matter of fact, two such racks and corresponding gears, one on each side of the table, will preferably be employed and the shaft or spindle 14, to which the gears are attached, is adapted to be oscillated through the medium of a lever 15 and a rod 16 that serves to connect such lever with the same drive that operates the picker fingers.

Fixedly mounted on the upper end of tubular shaft 5 is a tubular cap piece 20 provided with a rearwardly projecting bracket 21. Such bracket comprises an open framework, one essential element of which is a slot 22 that forms an open guideway inclining upwardly and rearwardly with respect to the main supporting shaft or column 5. Adjustably secured in such guideway, by means of a wing nut 23 or equivalent device, is a stud bolt 24 provided on its inner end with a roller 25 (see Figs. 5 and 5a), such roller engaging with a slot or rather a longitudinally extending groove 26 formed in one arm of a lever 27, the other arm of which is connected with a rod 28 whereby said lever is oscillated at intervals by the driving mechanism which remains to be described. Fixedly attached to said lever, co-axial with its normal axis of oscillation, is a tubular shaft 30 that projects at approximately a right angle from bracket 21 over the platen 1 of the printing press. The normal axis of oscillation of lever 25, it should be explained, is that wherein the stud bolt 24 is shown as being secured by wing nut 23 in all of the figures except Fig. 5a.

Shaft 30 is supported in bracket 21 by means of an outer surrounding sleeve 31 within which the shaft is free to rotate on occasion, such sleeve being in turn attached to the bracket 21 by means of two horizontally extending guideways 32 that permit said sleeve a bodily transverse movement or movement of translation in a plane inclined slightly from the horizontal, as shown in Fig. 1.

Further operative connection between the sleeve and such bracket is provided in the form of two spur pinions 33, one near each end of said sleeve, that mesh with corresponding racks 34 disposed alongside of guideways 32 so that upon the aforesaid bodily movement of the sleeve 31, and thus of shaft 30, within the confines of such guides, a rotative movement will be simultaneously imparted to such sleeve and shaft whereby the latter is oscillated through a limited arc.

Fixedly attached near the outer end of tubular shaft 30 is a transverse arm 35 that will of course be oscillated upon oscillation of the shaft and likewise partake of any movement of translation of such shaft transversely of its axis. A cross rod 36 is attached to the outer, i. e., lower, end of arm 35, and to the respective portions of such rod, that lie on either side of the arm, are secured sheet engaging and moving fingers in the form of suction tips 37 that may be adjustably positioned along said rod as desired and also secured in proper angular position about the same by means of set screws 38. The branches of a flexible hose 40, that lead from the outer end of shaft 30, are connected with said tips, respectively, another similar flexible hose 41 serving to connect the interior of said shaft 30 with the interior of the vertical tubular shaft 5 that forms the main support for the mechanism. Communication between such flexible connection 41 and the interior of said shaft 5 is controlled by a second tubular shaft 42 reciprocable within said last named shaft 100 and provided near its upper end with a port 43 adapted to register with a port 44 in said shaft 5, through which connection is had with duct 41. The upper end of said tubular shaft 42 is closed and is preferably given the inclined or diagonal form shown in Figs. 1 and 4, while its lower end 42a projects beyond the lower end of shaft 5 and is adapted to be connected with a suitable suction line (not shown). In the lowered position of said inner shaft 42, as illustrated in Figs. 1 and 4, for example, such port 44, it will be observed, is open to atmosphere, but upon the inner shaft being raised until the port 43 registers with such port 44, suction will be applied through duct 41, shaft 30 and branched duct 40 to the suction tips 37.

Oscillation of lever 27 and reciprocation of the inner tubular shaft 42, just described as controlling the application of suction to the picker fingers 37, as also oscillation of lever 15, whereby the table that supports the blank sheets is alternately advanced and retracted, are all derived from a transverse driving shaft 50 journaled in suitable bearings 51 on the main frame of the press, the right hand end of said shaft, as viewed in Fig. 2, being connected by means of suitable gears 52 with the so-called large gear 53 of the press. Said shaft 25, it will thus be seen, is rotated in

unison with the movements of the various parts of the press, including platen 1. At its opposite end, the left, as viewed in Fig. 3, the shaft in question carries two cams 54 and 55, such first named cam being formed with grooves on its respective faces wherein travel rollers on levers 56 and 57 that are pivotally attached to the plate 6. To the first of such levers is connected the rod 16 whereby lever 15 is oscillated and thus the table 9 reciprocated; while to the other lever 57 is attached the lower end of the rod 28 that is connected to oscillate lever 27. Co-operative with the periphery of face cam 55 is a roller on one end of a bell crank lever 58 that is pivotally attached to plate 6, just as are levers 56 and 57, the other end of said lever 58 having a forked connection with the lower end 42a of the inner tubular shaft that serves in effect as a valve to control the application of suction to the picker fingers.

The operation of the machine as a whole may now be set forth, so far as not already indicated in the description of the construction and operation of the several component parts. With the stud bolt 24 and the roller 25 carried thereby secured in the lower end of guideway 22, so that the axis of said roller is aligned with that of horizontally extending tubular shaft 30, the oscillation of lever 27, effected through the driving connections just described, will produce an identical oscillatory movement of said shaft 30 and will correspondingly swing the arm 35 on said shaft, together with the suction fingers carried by the latter, from a position where the latter are disposed in front of the stack of paper on table 9, as shown in dotted outline in Fig. 1, to a position approximately normal to the face of the platen, as shown in full lines in the figure just mentioned. Simultaneously with the bringing of the suction fingers into such first mentioned position, the lever 15 is rocked so as to advance the table, and thus the stack of paper thereon, sufficiently to permit the foremost sheet of the stack to be detached, as shown in Fig. 7, upon applying suction to the tips. Such application of suction is timed through reciprocation of the inner tubular shaft 42 to occur when the suction tips are thus properly positioned and the table 9 has been advanced, and suction is maintained pending the subsequent swinging of the tips into the full line position shown in Fig. 1, following which the inner tubular shaft 42 is dropped until port 44 is uncovered and the sheet thus released from the suction tips through the restoration of atmospheric pressure within tubular shaft 30 and the ducts leading therefrom to said tips.

When it is desired to vary the position transversely of the platen of the sheet deposited thereon, this is accomplished by shifting the location of the stud bolt 24, and thus the roller 25, along guideway 22. When the

roller, for example, is moved into the position shown in Fig. 5a and there secured by means of wing nut 23, the effect of oscillating lever 27 will be modified due to the dislocation of its axis of oscillation, which of course will be about such roller, and thus spaced more or less from the axis of shaft 30. The latter, together with the sleeve 31, whereby it is supported in the guideways 32 on bracket 21, will be caused to travel back and forth in such guideways as the lever is oscillated, the amount of such back and forth travel depending upon the distance the roller 25 has been shifted from its normal position.

It will be noted that as a result of the foregoing construction it is possible to vary the position of the sheet as deposited on the platen while always bringing the suction fingers or tips 37 back to the same starting point or pick-up position in relation to the stack of sheets on table 9. In other words, when the location of the stud bolt 24 and thus of roller 25 is shifted along guideway 22, the shaft 30, wherefrom the arm 35 that carries said suction tips is supported, partakes not merely of an oscillatory movement about its axis, but also as a movement of translation in a direction transverse of such axis. A similar compound movement is accordingly imparted to the suction tips with the result that, as stated, the range of movement of the latter may be varied to deposit the sheet where desired on the platen without changing the starting point of such movement, or in other words the pick-up position of the suction tips.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

1. In mechanism of the character described, the combination of a horizontally extending member carrying a suction finger; and supporting means for said member, said means being arranged and constructed to permit said member to have combined oscillatory movement about its own axis and rectilinear bodily movement transversely of its axis, whereby sheets may be transferred successively from a point of supply to the platen.

2. In mechanism of the character described, the combination of a horizontally extending member carrying a suction finger; and supporting means for said member, including a guideway wherein said member is permitted bodily movement transversely of its axis, said member being oscillatory about its axis at any point in such guideway, whereby sheets may be transferred successively from a point of supply to the platen.

3. In mechanism of the character de-

scribed, the combination of a horizontally extending shaft carrying a sheet engaging and moving finger; and supporting means for said shaft including a sleeve wherein said shaft is oscillatorily held, and a guideway for said sleeve disposed transversely of the axis of said shaft, whereby sheets may be transferred successively from a point of supply to the platen.

4. In mechanism of the character described, the combination of a horizontally extending shaft carrying a sheet engaging and moving finger; and supporting means for said shaft including a sleeve wherein said shaft is oscillatorily held, two laterally spaced guideways for said sleeve disposed transversely of the axis of said shaft, pinions fixed on said sleeve, and racks parallel with said guideways in mesh with said pinions, whereby sheets may be transferred successively from a point of supply to the platen.

5. In mechanism of the character described, the combination of a horizontally extending shaft carrying a sheet engaging and moving finger; supporting means for said shaft including a guideway wherein said shaft is permitted bodily movement transversely of its axis, said member being oscillatorily about such axis at any point in such guideway; a lever attached to said shaft; and a shiftable pivotal axis for said lever, whereby sheets may be transferred successively from a point of supply to the platen.

6. In mechanism of the character described, the combination of a horizontally extending shaft; a transverse arm on said shaft; a sheet engaging and moving finger carried by said arm; supporting means for said shaft including a sleeve wherein said shaft is oscillatorily held, two laterally spaced guideways for said sleeve disposed transversely of the axis of said shaft, pinions fixed on said sleeve, and racks parallel with said guideways in mesh with said pinions; a lever attached to said shaft; and a shiftable pivotal axis for said lever, whereby sheets may be transferred successively from a point of supply to the platen.

7. In mechanism of the character described, the combination of a horizontally extending shaft; a transverse arm on said shaft; a sheet engaging and moving finger carried by said arm; supporting means for said shaft including a sleeve wherein said shaft is oscillatorily held, two laterally spaced guideways for said sleeve disposed transversely of the axis of said shaft, pinions fixed on said sleeve, and racks parallel with said guideways in mesh with said pinions; a lever attached to said shaft and having an arm projecting radially therefrom; and a shiftable pivot engaging said arm, whereby sheets may be transferred successively from a point of supply to the platen.

8. In mechanism of the character described,

the combination of a horizontally extending shaft; a transverse arm on said shaft; a sheet engaging and moving finger carried by said arm; supporting means for said shaft including a sleeve wherein said shaft is oscillatorily held, two laterally spaced guideways for said sleeve disposed transversely of the axis of said shaft, pinions fixed on said sleeve, and racks parallel with said guideways in mesh with said pinions; a lever attached to said shaft and having an arm formed with a slot extending in a radial direction with respect to said shaft; and an adjustably held pin having sliding pivotal engagement with such slot, whereby sheets may be transferred successively from a point of supply to the platen.

9. In mechanism of the character described, the combination of a horizontally extending shaft; a transverse arm on said shaft; a sheet engaging and moving finger carried by said arm; supporting means for said shaft including a sleeve wherein said shaft is oscillatorily held, two laterally spaced guideways for said sleeve disposed transversely of the axis of said shaft, pinions fixed on said sleeve, and racks parallel with said guideways in mesh with said pinions; a lever attached to said shaft and having an arm formed with a slot extending in a radial direction with respect to said shaft; a fixed guideway disposed at an angle with respect to such slot; and a pin adjustably secured in said guideway and having sliding pivotal engagement with such slot, whereby sheets may be transferred successively from a point of supply to the platen.

10. In mechanism of the character described, the combination of a vertically extending main support; a cap-piece on said support having a bracket projecting therefrom formed with an inclined slot and with a horizontally extending guideway; a sleeve capable of rolling movement back and forth in such guideway; a shaft rotatably mounted in said sleeve and carrying a sheet engaging and moving finger; a lever attached to said shaft and formed with a slot extending in a radial direction therefrom; and a pin adjustably secured in the aforesaid inclined slot and having sliding pivotal engagement with such last mentioned slot, whereby sheets may be transferred successively from a point of supply to the platen.

11. In mechanism of the character described, the combination of a reciprocable table for blank sheets; an oscillatory member carrying a sheet engaging and moving finger adapted in one position to present such finger in operative relation to the outer sheet on said table, said member also having a bodily movement transverse of its axis of oscillation; means adapted simultaneously to oscillate said member and thus bodily to move the same; and other means adapted to advance

and retract said table in proper synchronism with the movements of said member.

12. In mechanism of the character described, the combination of a vertically extending main support; a secondary support movable thereon in a transverse direction; a horizontally extending shaft oscillatory in said secondary support; and a sheet engaging and moving finger carried from said shaft, whereby sheets may be transferred successively from a point of supply to the platen.

13. In mechanism of the character described, the combination of a vertically extending main support; a secondary support movable thereon in a transverse direction; a horizontally extending shaft oscillatory in said secondary support; a transverse arm depending from said shaft; a cross-rod attached to the free end of said arm; and sheet engaging and moving fingers secured to said cross-rod so as to be adjustable along the same, whereby sheets may be transferred successively from a point of supply to the platen.

Signed by me, this 5th day of August, 1929.
